DESIGN FOR A COMBINED COSMETIC CONTAINER AND APPLICATOR

Eugene E. Munk, Chicago, Ill., assignor to Imp Company, Chicago, Ill.

Application October 18, 1940, Serial No. 95,914

Term of patent 7 years

To all whom it may concern:

Be it known that I, Eugene E. Munk, a citizen of the United States of America and a resident of the city of Chicago, county of Cook, and State of Illinois, have invented a new, original, and ornamental Design for a Combined Cosmetic Container and Applicator, of which the following is a specification, reference being had to the accompanying drawing, forming part thereof.

In the drawing:

I claim:

The ornamental design for a combined cosmetic container and applicator, substantially as shown.

EUGENE E. MUNK.
